[57] **CLAIM**

The ornamental design for a motorcycle monobody with gas tank, as shown.

DESCRIPTION

FIG. 1 is a perspective view of a motorcycle monobody with gas tank showing my new design;

FIG. 2 is a top view thereof;

FIG. 3 is a front view thereof;

FIG. 4 is a right side view thereof;

FIG. 5 is a left side view thereof;

FIG. 6 is a rear side view thereof; and,

FIG. 7 is a bottom view thereof.

The broken lines shown in the FIG. 1 drawing view are for illustrative purposes only and form no part of the claimed design. The bottom view of the design is a plain and unornamented.

1 Claim, 2 Drawing Sheets
